UNITED STATES PATENT OFFICE.

WILLIAM C. SUPPLER, OF BIRMINGHAM, ALABAMA.

FLEXIBLE COUPLING.

Application filed August 18, 1924. Serial No. 732,648.

To all whom it may concern:

Be it known that I, WILLIAM C. SUPPLER, a citizen of the United States, and resident of Birmingham, Alabama, have invented certain new and useful Improvements in Flexible Couplings, of which the following is a specification.

This invention relates to improvements in couplings and particularly to that type of coupling in which there can be a slight misalignment between the coupled shafts. The coupling is provided with resilient members adapted to cushion shocks in starting and stopping.

15 An embodiment of the invention is illustrated in the accompanying drawings in which—

Fig. 1 is a side view partly in section;

20 Fig. 2 is an end view with parts broken away;

Fig. 3 is a perspective view of the head end of one of the coupled shafts;

25 Fig. 4 is a perspective view of one of the cushions used in the coupling;

Fig. 5 is a fragmentary view illustrating a modification;

Fig. 6 is a detail of a part shown in Fig. 5.

Referring particularly to the drawings 10 and 12 are shafts which are substantially in axial alignment. They are provided with heads 14 and 16 which are keyed or otherwise fixed thereto. Each head is provided with a number of lugs 18 which in end view are undercut or dove-tailed. Surrounding the lugged portions of the heads 14 and 16 is a sleeve 20 whose length is greater than the combined width of the lugs carried by the two heads. This sleeve is provided with inwardly extending lugs 22, which as shown in Fig. 2, lie midway between the lugs 18 carried on the heads 14 and 16. Interposed between each lug 18 and each lug 22, is located a cushion 24 formed of suitable resilient material, such as rubber, hydraulic packing or the like.

As shown in Fig. 4, these cushions are prismatic in form and the co-acting walls of the lugs 18 and 22 are so arranged that they seat squarely against the side faces of such prismatic cushions. By proportioning the parts in this way, I can use stock material for forming these cushions which are square in section, thus being unnecessary to provide special molds for the formation of the cushions, resulting in economy of manufacture.

Rings 26 are provided for retaining the cushions in place, these rings seating against shoulders 28 formed in the inner bore of the sleeve 20. Spring rings 30 are seated in suitable grooves for locking the retaining rings in place. As shown in Fig. 2 each spring ring has one end 32 which enters a suitable hole in the sleeve, and its other end 34 is bent inwardly to form a hook or loop for the insertion of a tool whereby the ring may be removed.

Or as illustrated in Figs. 5 and 6 I may provide a spring ring 34 which serves as a keeper or retaining ring, thus doing away with the necessity of providing an extra ring such as shown at 26, Fig. 1.

In operation, motion is transmitted, for example, from the head 14 through the cushions 24 to the other head 16 carried by the 75 shaft 12. There is a slight clearance between the two heads and consequently a large degree of flexibility is obtained. Due to the resiliency of the cushions 24, shocks are absorbed and a substantially uniform 80 torque is transmitted.

The coupling is of simple design not requiring the use of bolts or nuts in assembling and is devoid of projecting parts which would be apt to catch in the clothing of 85 workmen. The parts can be quickly and easily assembled, and can be manufactured at slight cost, yet performing their functions equally as well as more complex devices heretofore purposed.

Though I have described with great particularity the specific embodiments of the invention herein shown, it is not to be construed that I am limited hereto as changes in arrangement and substitution of equivalents may be made by those skilled in the art without departure from the invention as defined in the appended claims.

What I claim is:

1. A shaft coupling comprising heads secured to the ends of adjacent shafts, a sleeve surrounding said heads, inwardly projecting lugs on the latter, outwardly extending lugs on said heads located between the lugs on the sleeve prismatic cushions engaging the 105 sleeve lugs and the head lugs and retaining means for said cushions seated in said sleeve.

2. A shaft coupling comprising complementary heads of similar form secured to the ends of adjacent shafts, a sleeve surrounding said heads, lugs on said heads and said sleeve with cushioning members between 110

- them, keeper rings holding the latter against endwise movement and means for locking the keeper rings within said sleeve.
3. A shaft coupling comprising lugs on the ends of adjacent shafts, a sleeve having lugs located between the shaft lugs, resilient prismatic members interposed between the shaft and sleeve lugs, keeper rings and resilient means for locking the latter to said sleeve.
4. A shaft coupling comprising two heads whose end faces are of substantially or approximately identical contour being approximately circular with radially extending lugs, a sleeve encircling said heads and having radially extending lugs, prismatic blocks of resilient material between the respective sleeve and head lugs and resilient members engaging said sleeve for retaining said blocks.
5. A shaft coupling comprising two heads whose end faces are of substantially or approximately identical contour being approximately circular with radially extending lugs, a sleeve encircling said heads and having radially extending lugs, prismatic blocks of resilient material between the respective sleeve and head lugs the length of
- 30 said sleeve being greater than the combined thickness of both heads and means for holding the parts assembled without the use of bolts or screws comprising keeper rings engaging the sleeve lugs and spring rings engaging the sleeve to lock said keeper rings against outward movement.
- 35 6. A shaft coupling comprising a sleeve for transmitting power from one shaft to another, lugs carried by each shaft and by said sleeve, blocks of resilient material between the shaft and sleeve lugs, and a spring ring for holding the parts assembled.
- 40 7. A shaft coupling comprising a sleeve for transmitting power from one shaft to another, heads carried by each shaft and having outwardly extending lugs, inwardly extending lugs on said sleeve between said first named lugs, blocks of resilient material between the respective sets of lugs and spring members engaging said sleeve for restricting the longitudinal movement of 45 said heads away from each other within determined limits.
- 50 In witness whereof, I have hereunto signed my name.

WILLIAM C. SUPPLER.
